UNITED STATES PATENT OFFICE

FRANK STONER, OF LAKEWOOD, OHIO, ASSIGNOR TO THE BAKER-RAULING COMPANY,
OF CLEVELAND, OHIO, A CORPORATION OF OHIO

LOAD-HANDLING MECHANISM

Application filed August 8, 1924. Serial No. 730,931.

This invention relates to a load handling mechanism, whereby a load or loads may be readily raised and lowered, or transported from one place to another, and discharged.

5 One object of the invention is to provide an improved mechanism of this character capable of handling loads under varying conditions.

Another object of the invention is to provide improved means for adjustably supporting the boom at varying positions vertically whereby it may be operated under varying conditions without changing the size of the boom or lengthening or shortening it as the 15 case may be.

A further object of the invention is to correlate or associate the load lifting means with the boom support in order that the former may be utilized to elevate or adjust the boom 20 to the desired operating position.

Other objects of the invention will be apparent to those skilled in the art to which my invention relates from the following description taken in connection with the accompanying drawings, wherein

Fig. 1 is a side elevation of a truck and a load handling mechanism embodying my invention.

Fig. 2 is an end elevation of the truck and load handling mechanism (with parts broken away), the latter being shown slewed or swiveled about its pivot to one operative position to illustrate its manner of use.

Fig. 3 is a fragmentary view, partly in section on the line 3—3 of Fig. 1 and partly in elevation of the truck and load handling mechanism, looking at the other end of the truck.

Fig. 4 is a top plan of parts shown in Figs. 40 1 and 2.

Fig. 5 is a section on the line 5—5 of Fig. 1.

In the drawings, 1 indicates a frame of any desired shape and form, preferably constructed from channel and angle bars suitably connected by rivets or otherwise. In the illustrated form of construction the frame 1 comprises a main portion 1^a on which the mechanisms for raising and lowering loads and moving the load carrying member, to 50 be later referred to, are supported, and a

platform portion 1^b, on which loads may be placed; this latter frame portion serving as a supplemental support for a load, especially where it is necessary to transport the load to a distant point by the driving or operation of the truck. In this connection, it will be understood that the platform portion 1^b may be rigidly connected to the frame 1^a and it may be a continuation thereof or disposed in a plane therebelow, as shown in the drawings; or the platform portion 1^b may embody or have incorporated in or associated with it a superposed platform, which may be raised or lowered relative to the frame 1. Where the frame is constructed as shown in the drawings, I preferably provide a pair of relatively small trailing wheels 2 below the platform portion 1^b and a pair of relatively large wheels 3 below the main frame portion 1^a.

4 indicates a motor, the shaft of which is 70 connected by a suitable power transmitting mechanism with the axles of the wheels 3 to drive them in either direction, such mechanism being shown enclosed in a suitable housing member 4^a (see Fig. 2) rigidly connected to the casing of the motor 4. 5 indicates a mechanism of any desired construction interposed between the motor 4 and housing member 4^a and the frame 1 for connecting them together. The mechanism 5 may 75 be constructed to permit of relative movements between the motor and housing member and the frame 1 incident to the driving of the truck. 6 indicates pairs of casing elements enclosing springs 6^a between the frame 1 and the axle members connected to the housing member 4^a.

The outer ends of the axle members are shaped to form suitable knuckles 4^b on which the traction wheels 3 are pivoted for steering purposes, the connection between the wheels or the axles therefor and the power transmitting mechanism being of such character—universal joints for example—that the wheels may be driven while being steered. 8 indicates the axle for the trailing wheels 2. The opposite ends of the axle 8 are preferably shaped to provide suitable knuckles, which serve as pivotal supports for the wheels 2, whereby they may be steered and thereby 100

enable the truck to be turned in areas of relatively small dimensions. 9 indicates steering connections between the wheels 2 and wheels 3, whereby both pairs of wheels may be simultaneously operated about their pivots for steering purposes. The connections 9 include a tie rod 9^a between the wheels 3 and a tie rod 9^b between the wheels 2. 11 indicates a support on which the operative stands while operating the truck. The platform 11 is preferably pivoted to a rod 12, the opposite ends of which are supported in suitable brackets 13 secured to the lower end of a pair of uprights 14. By pivoting the platform 11, it may be swung upwardly—see dotted lines in Fig. 1—when the truck is not in use. The uprights 14 may comprise spaced angle bars rigidly secured to certain of the longitudinal or transverse sills of the frame 1 and extend upwardly to form a support for a dash 15. 16 indicates a foot pedal associated with the platform 11, and arranged to control the release and application of a brake mechanism, indicated as an entirety at 17. The pedal 16 is preferably mounted on the rod 12 so that it may readily swing upwardly with the platform 11 for reasons already set forth.

The brake mechanism 17 is arranged to brake the movement of the truck or to hold it against movement, its operating elements being so arranged and connected to a suitable spring not shown that the latter normally acts to apply the brake and to swing the pedal 16 upwardly, as shown in Fig. 1. Accordingly, movement of the pedal 16 downwardly, will release the brake. As a result of this arrangement, the truck is held against movement in either direction at all times and can only be moved upon the positive operation of the pedal 16. The brake mechanism 17 is preferably constructed to act on an element driven directly by the motor, for example a wheel or pulley 18 fixed to the extended rear end of the motor shaft.

23 indicates as an entirety a controller for cutting in or closing the circuit to the motor 4 to operate it at different speeds and in opposite directions, in a well known manner. The controller is operated by a shaft 24 carrying an arm 25, which is connected by a link 26 to a lever 27. The lever 27 is pivoted on the dash 15 to swing in vertical planes. 28 indicates as an entirety a switch mechanism associated with the controller 23 and brake mechanism 17, and automatically controlled by the latter through a rod 28^a to break the circuits to the controller or to the motor when the brake is on and to close the circuit when the brake is released, the purpose being to prevent operation of the motor 4 by means of the controller if the latter is moved from its "off" position in either direction when the brake is in its applied position. By preference, the switch mechanism is interconnected with the con-

troller by means of a link 28^b to prevent closing of the circuit in the event the controller lever is in or is moved to an "on" position and attempt is made to release the brake. As this mechanism does not form part of the present invention, but is described and claimed in Letters Patent No. 1,710,071 granted to Edward H. Remde, further description thereof is thought to be unnecessary.

29 indicates a post or steering column rotatably mounted in suitable bearings 29^a, 29^b, and connected by an arm 30 and link 31 with the steering connections. The upper end of the column 29 has connected to it a hand lever 32.

33 indicates an axle or pivot member disposed in vertical position on the main frame portion 1^a and extending upwardly therefrom to form a vertical shaft for a frame 34. The lower end of the shaft 33 is fitted into a sleeve 35 which in turn may be flanged at its opposite ends as shown at 35^a and fixed or seated between certain of the longitudinal sills constituting the main frame portion 1^a and platform portion 1^b. The frame 34 comprises a base section 34^a, having cross bars forming a support for a box containing a battery or batteries 36 and pairs of upright members 37, 38, connected by upper and lower horizontal members 39, 39'. The uprights 37, 38, are rigidly secured to base section 34^a in any desired manner. 39^a indicates plates disposed at the joints between the horizontal members 39' and upright members 38 and serving as a connection for a tie-bar 39^a extending from the plate 39^a to the upper end of the adjacent upright 37. 38^a indicates a gusset disposed at the joint between each upper horizontal member 39 and the adjacent upright 38. 38' indicates a shaft extending at its opposite ends through openings formed in the uprights 38, near their upper ends. The purpose of the shaft will later appear. To provide sufficient bearings for the shaft, I secure to the uprights hollow bosses 38^a into which the shaft ends extend (see Fig. 1). The pairs of upright members 37, 38, are arranged at points intermediate the front and rear end of the base section 34^a to provide space for supporting a load supporting member, such as a boom 40, and a motor 41, a power transmitting mechanism 42 and operating means 43, 44, which will later be described. The base section 34^a is formed near its front end and between the upright members 37, with an opening, which receives a bearing collar 46 to rotatably engage a bearing provided on the shaft 33, the collar 46 being provided with a flange by means of which it is bolted to the underside of the base section 34^a.

47 indicates a gear fixed to the collar 46. The gear 47 preferably fits and is suitably secured in an annular recess formed in the lower end of the collar 46 or a ring fixed thereto. The gear is engaged by a pinion which serves as a suitable element by means of which the

frame or support 34 is rotated in either direction about the shaft 33 by suitable power means (not shown). The power means is preferably operated by an electric motor which in turn is controlled by a controller 76^a. The controller is operated in either direction by a lever 76^b mounted on the dash 15 and connected to the shaft of the controller by connections 76^c (see Fig. 2). The motor 10 may be driven in either direction and it in turn through the power means will rotate or slew the frame 34 to either side of the truck frame 1, as desired, as shown in Fig. 2. Intermediate its ends the upright members 37 15 support a bearing box 50, which receives the upper end of the shaft 33 and co-operates with the collar 46 to form spaced bearings between the shaft 33 and the support or frame 34 for the latter to rotate on. The opening 20 for the collar 46 and shaft 33 is preferably arranged near the front end of the frame 34 so as to be substantially centrally of the weight of the batteries 36, motor 41 and power transmitting mechanism 42 and the boom 40 25 and the load carried thereby, so that those elements on one side of the pivot or shaft 33 will tend to counter-balance those on the other side thereof.

51, 51, indicate a pair of vertical plates 30 spaced from each other and mounted on the frame 34, preferably on a plate 34' extending across its front end. The plates 51 are secured to the plate 34' and base section 34^a by angle plates 51^a; and along their inner longitudinal portions they are riveted to the inner faces of the uprights 37 (as shown in Fig. 1) which are preferably formed from channel bars for a reason which will presently appear. 51^b indicates angle bars disposed 35 along the outer longitudinal edges of the plates 51, each angle bar being positioned so that one wall of the bar may be riveted to the plate, as shown in Fig. 5, and its other wall project laterally outwardly, so that it 40 may co-operate with the plate 51 and outer flange 37' of the adjacent upright 37 to form a guide 51^c, the purpose of which will later be set forth. 51^d indicates a plurality of cross bars extending between and secured at their 45 opposite ends to the angle bars 51^b and serving to support them and the plate 51 in alignment. 51^e indicates pairs of aligned openings formed in the guides 51^c, preferably midway between the angle bar 51^b and the flange 37'; one pair of openings being formed adjacent the lower ends of the guides and the remaining pairs being arranged along the upper portions of the guides, although a larger number may be provided, if desired. 55 The openings 51^e serve to receive a rod 52, to which reference will later be made. The walls of the openings 51^e are preferably reinforced by plates 52' secured to the inner faces of the plates 51 in any desired manner. 60 The boom 40 preferably comprises a pair of channel members 40^a arranged in spaced relation, but slightly converging toward their upper ends. The upper portions of the members 40^a may be curved forwardly and downwardly. The channel members are secured 70 together in spaced relation by a plurality of cross-pieces 40^b, 40^c, 40^d and diagonal pieces 40^e, 40^f. At a point remote from their free ends, the members 40^a are provided with 75 upstanding plates 53, the purpose of which will later appear. 52^x indicates as an entirety a supporting means for the boom 40 and slidably mounted in the guides 51^c to be adjusted therein and fixed thereto at any desired position intermediate its ends, the purpose being 80 to raise and lower the fulcrum of the boom 40 so that the operating end of the latter and the load engaging member suspended therefrom may be adapted for various conditions without the necessity of substituting 85 a new boom or changing its length. Of the supporting means 52^x, 52^a indicates a pair of plates having flanges 52^b along their opposite longitudinal edges and slidably fitting the guides 51^c. At their lower ends the plates 90 52^a are provided with hollow bosses 52^{b'} (preferably formed integrally therewith), which support the inner ends of tubular bearing members 52^c. The inner ends of the bearing members 52^c are flanged and fit within 95 annular recesses formed in the inner wall of the bosses 52^b to hold the members against movement outwardly. The outer ends of the bearing members 52^c extend through knuckles 100 40^x provided on the lower or inner ends of the channel bars 40^a, so as to form a fulcrum for the boom 40. As shown in Fig. 5, the rod 52 extends through one pair of the openings 51^e and tubular bearing members 52^c and thereby connects the supporting means 52^x 105 to the guides 51^c. By removing the rod 52 and adjusting the supporting means 52^x along the guides 51^c to align the tubular bearing members 52^c with another pair of openings 51^e and then inserting the rod 52 therein, the 110 fulcrum for the lower end of the boom will be adjusted to position its operating end at a greater or lesser height according to the adjustment referred to. The opposite ends of the rod 52 are provided with removable devices, such as cotter pins, to prevent its endwise movement. The boom is swung upwardly and downwardly about its fulcrum by any suitable means, but preferably by means of a cable or other flexible connection 40' connected to the operating means 43. 115 55 indicates as an entirety a member for engaging a load, whereby the load may be raised or lowered or otherwise handled. The load engaging member may be of any desired construction, such as a clam shell bucket or a platform, but for illustrative purposes I have shown such member as comprising a hook depending from a casing 56, which in turn is supported or suspended from the free end of 120 125 130

the boom 40 by a cable or other flexible connection 57, connected with the operating means 44 as will be later described.

The operating means 43, 44 comprise a pair of drums 58, 59, on which the cables 40', 57, respectively, wind and unwind, for swinging the boom 40 about its pivotal support and for raising or lowering the load engaging member 55. The drums 58, 59, are rotated independently of each other in either direction in the manner to be later set forth, to swing the boom 40 and raise or lower the member 55. The cable 40' may be connected at its inner end to the drum 58 in any desired manner. From the drum 58 the cable 40' leads to and around a sheave 40'', rotatably supported on the shaft 38'; it then reeves through and around a plurality of sets of sheaves 61, 62, supported in suitable blocks, respectively, as clearly shown in Fig. 1, operatively connected with the frame 34 and plates 53. The opposite or outer end of the cable is carried down and connected or anchored in any suitable manner.

The cable 57 is connected at its inner end in any suitable manner to the drum 59. From the drum 59, the cable 57 runs around a guide sheave 69, supported on and near the upper end of the adjacent upright member 37, and then around a sheave 70 loosely mounted on the adjacent tubular member 52'. From the sheave 70 the cable 57 extends over a sheave 71, rotatably mounted on a rod 68, which is supported at its opposite ends by the plates 53. From the sheave 71 the cable reeves around a sheave 72 supported in the free end of the boom 40, then around a sheave 73 mounted in the casing 56, and then around a sheave (not shown) supported in the free end of the boom 40, the outer end of the cable being carried down and connected by a socket and loop to the shaft of the sheave 73.

102 indicates as an entirety a casting shaped and constructed to form a cradle 102^a for the motor 41 and a housing section 102^b for the power transmitting mechanism 42, by means of which either drum 58, 59, may be driven. The casting 102 is rigidly connected to disks 104, which are provided with integral extensions to provide feet 106, secured to angles 107 carried by the upright members 38. The feet 106 operate through the disks or members 104 and the housing and cradle casting 102 to support the motor 41 and power transmitting mechanism 42 in fixed relation upon the support 34 and in operative relationship to each other. The motor 41 is fixed to the cradle 102^a by a plurality of screws 107'. 108 indicates a housing section shaped to fit upon the open end of the housing section 102^b and be clamped thereto and also to enclose the propeller shaft connected to the shaft 109 of the motor 41. The housing section 108 is adapted to support a pair of spaced bearings for the pro-

peller shaft. Between the propeller shaft bearings, the shaft is provided with a worm 110 which meshes with and drives a ring gear forming one of the elements of the power transmitting mechanism 42.

The power transmitting mechanism 42 for the operating means 43, 44, may be of any desired construction. In practice I have used a well known type of differential mechanism, such as is commonly used for driving the wheels of automobiles. Such mechanism may be similar in construction to the usual differential mechanism utilized in the truck construction herein illustrated for driving the wheels 3 from the motor 4. By the use of a differential mechanism a single motor may be employed to operate the operating means through the co-operation of suitable devices and means for holding or releasing the driven elements of the differential mechanism, whereby either drum will be rotated in a simple manner. 125 indicates as an entirety suitable means for controlling the rotation of each drum 58, 59, so that when the motor 41 is driven in one direction or the other, it will transmit power through the differential of the mechanism 42 to rotate the drum which has been released, whereby one of the cables is wound thereon or payed-out to swing the boom or operate the member 55. Each controlling means preferably comprises a clutch and magnetically operated elements to release it, adapted to be connected in series with the motor 41 in such manner under the control of a selector or lever 143 that when the motor is operated either drum, at the will of the operative, is driven.

To carry out these operations, I provide (1) the lever 143, pivotally mounted on the dash 15 and connected through an arm 144 and link 145 with a crank arm 146, which is connected to the shaft of a controller indicated as an entirety at 147; and (2) a lever 148, pivotally mounted on the dash 15, and connected through an arm 149 and a link 150 with a crank arm 151 which is connected to the shaft of a switch device 152. The purpose of the controller 147 is to supply current to the motor 41 to drive it in either direction, such operation being dependent upon the movement of the lever 143 to either side of its neutral position, as shown in Fig. 2. The purpose of the switch device 152 is to select or connect in either of the magnetically controlled elements, dependent upon which one of the drums is to be operated, in series with the motor 41, so that upon the operation of the controller lever 143, the selected drum will be rotated in one direction or the other, according to the direction of movement of the lever.

As the power transmitting means 42, holding and locking means and release means, as well as the selector means is the invention of Edward H. Remde, and forms the subject-

matter of his co-pending application, Serial No. 679,605, no claim thereto is made herein.

The motor 41 is preferably of the electric type in order that it may be operated from the batteries 36 and co-operate with the drum controlling means herein referred to; but it will be understood that the controlling means and the motor may be operated in any other manner. The motor 41 may be of any desired construction. It preferably has associated with it a brake mechanism, indicated as an entirety at 153, to stop the rotation of its shaft and elements driven thereby following the opening of the motor circuit. Of the 15 brake mechanism 153, 154 indicates a brake wheel fixed to the motor shaft, which is extended beyond the upper end of the motor casing for this purpose. 155, 155^a, indicate brake shoes pivoted at corresponding ends 20 upon a shaft 156 mounted in a boss on the adjacent end of the motor casing. The opposite ends of the shoes are connected to a pair of levers 157, 157^a, which are so connected to each other that upon the movement of 25 the latter in one direction the levers will operate to clamp the shoes against the brake wheel. The lever 157^a is connected to one arm 158 of a lever 159, which is mounted upon a shaft 159^a suitably supported by the 30 motor casing. The arm 158^a of the lever 159 is connected to one end of a spring 160. The spring 160 operates to move the lever 157^a in that direction which applies the brake shoes and thus normally keeps the latter in 35 braking position. To release the brake shoes, the lever 159 is rocked about the pivot or shaft 159^a in the opposite direction, this operation being preferably effected by a solenoid 161, the core of which is connected by 40 a link 162 with the arm 158^c of the lever 159. The winding on the solenoid is connected in series with the circuit to the motor, so that when the circuit is closed the solenoid is energized and automatically effects the release 45 of the brake shoes; likewise, upon the opening of the motor circuit the solenoid winding is de-energized and thus permits the spring 160 to automatically actuate the brake shoes to clamp the brake wheel.

50 As will be understood from the foregoing description, the load is raised and lowered by winding the rope 57 on or unwinding it from the drum 59, the boom 40 is swung upwardly or downwardly by winding the rope 40' on or unwinding it from the drum 58 and the support 34 is swung or rotated about the shaft 33 by the driving of the gear 47. The movement of each of these elements is automatically stopped when moved in either direction (except in the downward movement of the load engaging element 55) at a predetermined position by a mechanism which includes a switch means that opens the circuit to the motor that operates such element. The switch means for stopping the move-

ments just referred to may be similar in construction, each being preferably similar in construction to the switch means which forms the subject matter of an application filed by the said Edward H. Remde, Serial No. 610,791 (see Letters Patent No. 1,726,717, dated September 3, 1929). The switch means for stopping the swinging or rotation of the frame 34 is indicated at 163'; the switch means for stopping the movement of the boom 40 is indicated at 165 and is arranged to be actuated by spaced tappets 167 on a rod 166; and the switch means for stopping the raising of the load engaging member or element 55 is indicated at 169, it being actuated by a spring 175 when the weight 174 is raised by the casing 56 to relieve pull of the cable 170 on the arm 171.

From the foregoing description it will be seen that I have provided a load handling mechanism in which the load may be moved or operated in any one of a plurality of directions in a rapid and simple manner, and that I am enabled to effect the various operations of the load engaging member and the boom from a single motor and a unitary driving or power transmitting mechanism, which tends toward economy and simplicity as well as compactness of the construction.

It will also be seen that by the provision of the vertical guides 51^c and a fulcrum or supporting means which adjustably engage therewith, I may bodily raise or lower the boom 40, thus enabling its free end and the load engaging member suspended therefrom to be adapted to handling loads under many different conditions, thereby avoiding the necessity of a truck carrying a different size boom, or substituting a new boom.

By positioning the sheave 69 at the extreme upper end of the upright 37 and the sheave 70 on the fulcrum for the boom 40, I may utilize the operating means 44 and load raising and lowering cable 57 operated thereby to raise and lower the boom supporting means 52^x to adjust it to the desired height, since the cable 57 reeves around these sheaves. In raising the supporting means 52^x, I first engage the hook 55 with one of the cross members of the boom 40, next I remove the rod 52 and then I rotate the drum 59 in the direction to wind the cable 57 thereon, the effect of which will be to slide the supporting means 52^x in the guides 51^c, such winding continuing until the supporting means 52^x is adjusted to the desired position, in alignment with a pair of openings 51^c', following which the rod 52 is replaced. In moving or adjusting the supporting means 52^x downwardly, I proceed in the same manner, but rotate the drum 59 in the opposite direction to pay out the cable 57. Due to the fact that the boom 40 is fulcrumed on the frame 34 and connected thereto through the cable 40', it is desirable to first swing the boom down-

wardly before effecting adjustment of its fulcrum upwardly and before adjusting its fulcrum downwardly, it is desirable to first swing the boom upwardly.

5 To those skilled in the art to which my invention relates many alterations in construction and widely differing embodiments and applications of the invention will suggest themselves without departing from the spirit and scope thereof. The disclosures and the description herein are purely illustrative and are not intended to be in any sense limiting.

10 What I claim is:

15 1. In apparatus of the class described, the combination of a frame, a vertically arranged guide, a boom, a support adjustably secured to said guide for supporting the lower end of said boom thereon, a flexible member extending downwardly from the outer portion of said boom and carrying an element arranged to engage a load or be anchored, sheaves around which said member reeves, one of said sheaves being supported above the upper limit of adjustment of said support along said 20 guide and the other sheave being mounted on said support, and mechanism for winding up or paying out said flexible member, whereby a load may be engaged and moved or, upon anchoring of the load engaging element, the 25 boom support may be adjusted to another position.

30 2. In apparatus of the class described, the combination of a frame, a guide on said frame, a slide movably engaging said guide, means for adjustably connecting said slide to said guide, a boom fulcrumed on said slide, a flexible member connected to said boom for swinging it about its fulcrum, a flexible member extending downwardly from the outer 35 portion of said boom and carrying an element arranged to engage a load or be anchored, sheaves around which the last mentioned flexible member reeves, one of said sheaves being supported above the upper limit of adjustment of said slide along said 40 guide and the other sheave being mounted on said slide, and a drum for winding up or paying out each of said members.

45 3. In apparatus of the class described, the combination of a frame, a supplemental frame rotatably mounted on said frame, a pair of vertically extending guides mounted on said supplemental frame, a boom, supporting means for the fulcrum of said boom adjustably engaging said guides, a load engaging member, means for rotating said supplemental frame, a sheave carried by said supporting means, a sheave carried by said supplemental frame above the limit of adjustment 50 of said fulcrum supporting means, and mechanism for operating said load engaging member, said mechanism including a flexible member running around said sheaves and connected to said load engaging member, whereby upon anchoring of said flexible member,

the operation of said mechanism will adjust said supporting means.

55 4. In apparatus of the class described, the combination of a frame, a supplemental frame rotatably mounted on said frame, a pair of vertically extending guides mounted on said supplemental frame, a boom, a pair of plates to which said boom is fulcrumed slidably engaging said guides, a device for removably connecting said plates to said guides, a load engaging member, means for rotating said supplemental frame, a sheave carried by one of said plates, a sheave carried by said supplemental frame above the limit of movement of said plates, and mechanism for operating said load engaging member, said mechanism including a flexible member running around said sheaves and connected to said load engaging member, whereby upon anchoring of said flexible member, and removal of said device, operation of said mechanism will slide said plates along said guides.

60 5. In apparatus of the class described, the combination of a frame, a pair of guides mounted on said frame, a boom, supporting means for the fulcrum of said boom adjustably engaging said guides, a load engaging member, a sheave carried by said supporting means, a sheave carried by said frame above the limit of adjustment of said fulcrum supporting means, and mechanism for operating said load engaging member, said mechanism including a flexible member running around said sheaves and connected to said load engaging member, whereby upon anchoring of the outer portion of said flexible member, the 65 operation of said mechanism will adjust said supporting means.

65 In testimony whereof, I have hereunto subscribed my name.

105 FRANK STONER.

CERTIFICATE OF CORRECTION.

Patent No. 1,757,150.

Granted May 6, 1930, to

FRANK STONER.

It is hereby certified that the name of the assignee in the above numbered patent was erroneously written and printed as "The Baker-Rauling Company", whereas said name should have been written and printed as "The Baker-Raulang Company", as shown by the records of assignments in this office; and that the said Letters Patent should be read with this correction therein that the same may conform to the record of the case in the Patent Office.

Signed and sealed this 24th day of June, A. D. 1930.

(Seal)

M. J. Moore,
Acting Commissioner of Patents.
